(57) **CLAIM**

The ornamental design for a cushion for vehicle seat, as shown and described.

DESCRIPTION

FIG. 1 is a front, right and top perspective view of a cushion for vehicle seat, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 2 comprising a buckle.

FIG. 10 is a partial enlarged view of an area labeled 10 in FIG. 2 comprising a fixed part.

FIG. 11 is a front, right and top perspective view of a second embodiment of a cushion for vehicle seat.

FIG. 12 is a rear, left and bottom perspective view of the second embodiment of the cushion for vehicle seat of FIG. 11.

FIG. 13 is a front elevation view of the second embodiment of the cushion for vehicle seat of FIG. 11.

FIG. 14 is a rear elevation view of the second embodiment of the cushion for vehicle seat of FIG. 11.

FIG. 15 is a left side elevation view of the second embodiment of the cushion for vehicle seat of FIG. 11.

FIG. 16 is a right side elevation view of the second embodiment of the cushion for vehicle seat of FIG. 11.

FIG. 17 is a top plan view of the second embodiment of the cushion for vehicle seat of FIG. 11.

FIG. 18 is a bottom plan view of the second embodiment of the cushion for vehicle seat of FIG. 11.

FIG. 19 is a partial enlarged view of an area labeled 19 in FIG. 12 comprising a buckle; and,

FIG. 20 is a partial enlarged view of an area labeled 20 in FIG. 12 comprising a fixed part.

The dot-dash boundary line in FIGS. 2, 9-10, 12, and 19-20 demarcates portion of the article annotated for enlargement purposes.
